INFANT'S FOLDING BATH STAND AND DRESSING TABLE

Charles T. De Puy, Brighton, and William C. Baxter, Rochester, N. Y., assignors to Trimble Nurseryland Furniture, Inc., Rochester, N. Y., a corporation of New York

Application April 22, 1946, Serial No. 664,131

1 Claim. (Cl. 211—149)

1

This invention relates to an infant's folding bath stand and dressing table, with particular reference to the type of construction employing a collapsible cross-legged stand with a flexible tub supported therebetween and a dressing table movably mounted thereon, and it has for its purpose to afford a simple, practical, and economical form of utility tray pivotally mounted between the innermost legs beneath the tub and adapted to be positioned horizontally when in use or folded to a position in alignment with the legs when the stand is collapsed.

A further purpose of the invention is to afford a construction that is particularly adapted to a utility tray formed of sheet metal such as aluminum and enables assembling such a metal tray readily so that it is permanently but firmly secured to the leg-frame.

Another object of the invention is to afford a simple and convenient means for controlling downward movement of the tray and holding it in horizontal operative position, such means being retracted into alignment with the leg-frames when the parts are folded and automatically movable to engage the tray and limit its movement when the latter drops into operative position.

Still an additional purpose of the invention is to afford a construction that is particularly useful in connection with metal leg-frames that are connected for folding through the instrumentality of pivot pins that extend inwardly from the legs and afford supports for the utility tray that is mounted thereon.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in end elevation of a folding bath stand and dressing table with a preferred embodiment of the invention incorporated therein and showing the parts in operative position;

Fig. 2 is a similar end view partially broken away, showing the leg-frames and utility tray in folded positions;

Fig. 3 is a horizontal sectional view on line 3—3 of Fig. 1 looking in the direction indicated and showing the tray in plan;

Fig. 4 is an enlarged detail sectional view taken longitudinally of the tray and centrally of its pivotal support;

Fig. 5 is a view in front elevation showing the tray in operative position in section, and

Fig. 6 is an enlarged detail view in side elevation, partially broken away, looking from left to right of Fig. 5, and showing in dotted lines the position of the tray as it is folded upwardly.

Referring more particularly to the drawings in which like reference numerals refer to the same parts throughout the several views, 1 and 2 designate the legs of the front leg-frame while 3 and 4 designate the legs of the rear leg-frame. Between the leg-frames is secured a flexible tub 5, while 6 designates a dressing table pivotally mounted on the rear leg-frame and adapted to be supported on the top rail of the front leg-frame when in horizontal position, as shown in Fig. 1. The dressing table may be elevated to upright position, such movement being limited by a screen 7 and screen frame 8 pivoted to the rear leg-frame, while 9 designates an actuating rod connected to an extension 10 on the hinge plate 11 of the dressing table and controlled by a treadle 12 pivoted to the leg-frame. 13 designates a controlling spring that is connected at its upper end to the extension 10 of the hinge plate and at its lower end to a fastening device on the adjacent leg. When the stand is to be folded, the dressing table is first elevated, the leg-frames are collapsed into parallel relationship, and the dressing table folded downwardly in front of the leg-frames to hold the latter in folded relation.

The parts thus far described are disclosed in Patent Number 2,481,577 of September 13, 1949, and the instant application has to do particularly with the construction of the utility tray employed for holding various toilet articles, pieces of clothing, or the like, and which will now be described in detail.

The utility tray, which is formed of sheet metal such as aluminum, comprises a bottom wail 14 that terminates at its edges in an integral curved rim formed by bending the outer edge portion of the tray upwardly, outwardly, and downwardly upon itself to afford an outer wall 15 spaced from and integrally connected to an inner wall 16, the tray being located and pivotally mounted between the inner legs 1 and 2 of the front leg-frame.

The legs are of metal such as aluminum of U-shaped cross-section with the open sides of the channels facing inwardly toward each other, and at their central portions, the channels of the legs are provided with wooden block inserts 17, while 18 designates bolts or pivot pins extending through the legs and blocks to pivotally connect the leg-frames and permit their collapsing. The

bolts or pins 18 are secured in position by means of the inner nuts 19 and the pins 18 extend beyond the nuts 19 inwardly of the leg-frames and toward each other to afford terminal portions which pivotally support the tray.

The distance between the two opposite end walls 15 of the tray is slightly greater than the distance between the innermost ends of the supporting pivot pins 18, and the marginal portion of the tray is sufficiently flexible to permit the walls 15 to be sprung inwardly in order to permit openings provided in the walls 15 to engage the inner ends of the pins or bolts 18, and the tray is thus securely and permanently held in position on the leg-frame.

It is desirable to provide simple and effective means for holding the utility tray in operative position and limiting its downward movement, and to accomplish this, each leg 1 and 2 has pivotally supported on its inner face at a point above the tray and forwardly of bolts 18, as on the pins 21, a supporting member in the form of a swinging gravity bar 22 which at its lower end is provided with an inwardly and upwardly projecting stop portion 23 that interlockingly engages the lower exposed edge of the wall 15 of the tray and extends upwardly between the spaced walls 15 and 16, as shown in Fig. 5.

Each gravity bar 22 is pivoted above and forwardly of the pivotal supports or pins 18, as shown in Figs. 1 and 6, and thus serves to hold the tray in horizontal operative position. The utility tray is free to move upwardly away from the stop portion 23 and so can be folded into parallel relation to the legs when the latter are folded, as in Fig. 2, and when in this position, the gravity locking bars 22 swing over to vertical position in alignment with the legs on which they are mounted. When the stand is unfolded for use, the locking bars 22 automatically swing by gravity to the vertical position illustrated in Fig. 1 and are thus in position to engage the bottom edges of the walls 15 of the tray as the latter drops to its horizontal position, beyond which it cannot travel because of the stop portions 23 on the locking bars.

While the invention has been described with reference to the particular construction shown, it is not confined to the details disclosed, and this application is intended to cover such changes or modifications as may come within the purposes of the improvement and the scope of the following claim.

We claim:

In an infant's folding bath stand and dressing table, the combination with inner and outer leg frames comprising metal legs of U-shaped cross-section with the open sides of the channels facing inwardly, wooden insert blocks at the central

portions of the legs, and pivot pins extending through and pivotally connecting adjacent legs and insert blocks of the leg frames to permit their collapsing, said pivot pins having exposed inner ends extending inwardly beyond the legs of the inner leg frame, of a sheet metal tray pivotally arranged between the legs of the inner leg frame and including a rim comprising an outer wall with an exposed bottom edge and an inner wall integrally connected to the outer wall by a curved top portion, said outer wall having lateral openings at opposite ends of the tray engaging the inner ends of said pivot pins and said outer walls being yieldable permitting the tray to be removably supported on said pivot pins by springing said walls over the ends of the pins, the distance between the end walls of the tray being slightly greater than the distance between the innermost ends of the pivot pins, and gravity-controlled supporting members comprising rigid bars pivoted to the legs of the inner leg frame at points above and forwardly of said supporting pins adjacent to the ends of the tray and having swinging movement in planes adjacent and parallel to the planes of the outer end walls of the tray, said rigid bars being disconnected from the tray and having inwardly and upwardly curved interlocking portions at their lower ends which act as weights to hold the bars at all times in vertical position and which automatically engage under and support the bottom edges of the outer end walls of the tray and are located between the outer and inner walls of the tray at points forwardly of said pivot pins when the tray is lowered and automatically assume a position in line with the adjacent legs when the leg frames are folded permitting free upward folding movement of the tray independently of the rigid supporting bars.
